(57) CLAIM

I claim the ornamental design for a wheeled abdominal exerciser, as shown and described herein.

DESCRIPTION

FIG. 1. Is a perspective view of the wheeled abdominal exerciser;

FIG. 2. Is a right-side view of the said embodiment, the left-side view being a mirror image;

FIG. 3. Is a top view thereof;

FIG. 4. Is a bottom view thereof;

FIG. 5. Is a front view thereof; and,

FIG. 6. Is a rear view thereof.

1 Claim, 2 Drawing Sheets

FIG. 3

FIG. 4

FIG. 6
